DOORSTOP

Wilfrid Desy, Detroit, Mich.

Application September 30, 1950, Serial No. 187,795

3 Claims. (Cl. 16—86)

1

This invention relates to a screen door stopper, and more particularly to a stopper construction adapted for mounting within a door jamb and which is cooperable with a portion of a closing screen door to prevent accidental or noisy closing thereof.

It is the object of the present invention to provide a very simplified screen door stopper which incorporates mechanism for absorbing the force of the closing door, to cushion the same and which will permit the noiseless closing thereof.

This and other objects will be seen in the following specification and claims in conjunction with the appended drawing in which—

Fig. 1 is a side elevational view of the screen door stopper as mounted upon a door jamb and showing the stopper engaging a closing screen door and also illustrating, in dotted lines, the relation of the screen door and stopper arm when the screen door is fully closed.

Fig. 2 is similar to Fig. 1 but illustrates the stopper arm projected longitudinally inward under the closing action of the screen door and locked against upward pivotal movement; and

Fig. 3 is a section on line 3—3 of Fig. 1.

It will be understood that the above drawing illustrates merely a preferred embodiment of the invention and that other embodiments are contemplated within the scope of the claims hereinafter set out.

Referring to Fig. 1 the screen door stopper includes the rectangular flat plate 13 secured in an upright position by the screws 14 to an interior side wall of the door jamb 11 and in association with the screen door 12 hinged relative to said door jamb.

The rivet 15 is joined to plate 13 and projects outwardly therefrom and has a headed portion 16 at its outer end. Elongated stopper arm 17 is pivotally mounted upon the rivet 15 and has a central rearwardly positioned elongated slot 18 which receives said rivet to permit longitudinal inward movement of arm 17 with respect to said rivet from the position shown in Fig. 1 to the position shown in Fig. 2.

Elongated rivet or shaft 19 is joined to and projects normally outward from the outer end of arm 17 and carries thereon the rotatable brass eyelet 21 and the soft rubber or resilient yielding wheel 20 which is adapted to engage the frame of the screen door 12.

The screen door stopper arm includes the forwardly arranged outturned reinforcing spaced side wall portions 22 which merge rearwardly into the rear side wall portions 23 of increased height as shown in Fig. 3. The stopper arm includes the top wall portions 24 which are bent inwardly

5 towards each other from the side wall portions 23 with their inner longitudinal edges spaced as shown in Fig. 2 and extending below the head 16 of rivet 15. The flange 25 is arranged centrally of arm 17 and is turned outwardly therefrom as shown in the drawings and as shown particularly in Fig. 3 in cooperation with the opposed top wall portions 24. The elongated bolt 26 is mounted upon the screen stopper arm 17 below the top wall portions 24 with its head bearing against rivet 15 and with its opposite threaded end extending slidably through a transverse opening in flange 25. The nut 27 is threaded upon the outer end of the bolt 26 and, in the 10 inoperative position shown in Figs. 1 and 3, engages flange 25.

Low tension coiled spring 28 is positioned around the bolt 26 with one end engaging the inner surface of flange 25 and with its opposite 15 end engaging the under surface of the head of bolt 26.

Spaced stops 29 and 30 project normally outward from plate 13 with stop 29 engaging arm 17 to limit its downward positioning as shown in 20 Figs. 1 and 2. Stop 30 limits the upward pivotal movement of the stopper arm 17 as shown by the dotted line illustration in Fig. 1.

There is also provided at the lower corner of plate 13 an upright stopper 31 which in the inoperative position of the door stop in Fig. 1 is clear of the rearward projection 32 of said arm but which, in Fig. 2, is in the path of pivotal movement of said projection, with the guide ledge 33 thereof operatively bearing against stopper 31.

In operation, as shown in Fig. 1 with the screen door fully closed, the arm 17 assumes the dotted line position illustrated. Upon opening of screen door 12, as shown in Fig. 1, the arm 17 pivotally drops as shown resting upon the stop 29 where it stays until the screen door swings closed in a conventional manner.

Without the present stopper construction, the screen door would noisily close against the door jamb 11 which is obviously objectionable. However by the present construction the resilient rubber wheel 20 will engage the closing screen door as shown in Fig. 1. The inward thrust of the door initially causes a partial collapsing of rubber wheel 20, which is preferably of soft rubber, and thereafter the thrust of the screen door projects the arm 17 rearwardly in a straight line to the position shown in Fig. 2.

This compresses spring 28 and at the same time the threaded end of the bolt 26 projects outwardly from the flange 25 as illustrated.

It is apparent from Fig. 2 that the extension 32 at the rear end of arm 17 and its guide ledge

33 bear against stopper 31 preventing arm 17 from pivoting upwardly under the action of the screen door in the first instance so that said arm acts as a stiffening rod to stop the door without noise.

As the door slightly bounces back under the action of low tension spring 28 to the position shown in Fig. 1 the door will have come to a dead stop and is now free to close to the dotted line position shown in Fig. 1 and this will project the stopper to the dotted line position shown. This is clear inasmuch as the projection 32 is now free of stopper 31.

Having described my invention reference should now be had to the claims which follow for determining the scope thereof.

I claim:

1. A screen door stopper comprising an upright plate secured within a door jamb, a headed pin projecting normally of said plate and secured thereto, an arm pivotally mounted at its inner end upon said pin and adapted to extend parallel to said plate and outwardly of said jamb, spaced first stops projecting normally from said plate upon opposite sides of said arm and lying in its path of pivotal movement and alternately engageable by said arm to limit pivotal movement thereof, one of said stops underlying and normally supporting said arm whereby upward pivotal movement thereof will be limited by another of said stops, a soft rubber wheel journaled upon the outer end of said arm and engageable with a closing screen door to absorb the thrust thereof and permit the said door to quietly close, pivoting said arm upwardly within the door jamb, said arm having a central elongated slot adjacent its inner end to receive said pin to permit an initial longitudinal inward non-pivotal movement of said arm upon initial engagement of said wheel with said screen door, a coiled spring supported upon said arm and interposed between said pin and said arm normally resisting said initial longitudinal inward movement of said arm and adapted to return the arm to its initial position as the screen door comes to a dead stop, and a stopper projecting normally from said plate rearwardly of said pin and arranged normally in spaced relation to the inner end of said arm but in its path of pivotal movement when said arm is moved longitudinally inward whereby upon said initial longitudinal inward movement of said arm said stopper engages its inner end preventing pivotal movement thereof and said spring will return said arm to its initial position for pivotal movement upwardly upon subsequent closing movement of said door.

2. A screen door stopper comprising an upright plate secured within a door jamb, a headed pin projecting normally of said plate and secured thereto, an arm pivotally mounted at its inner end upon said pin and adapted to extend parallel to said plate and outwardly of said jamb, spaced first stops projecting normally from said plate upon opposite sides of said arm and lying in its path of pivotal movement and alternately engageable by said arm to limit pivotal movement thereof, one of said stops underlying and normally supporting said arm whereby upward pivotal movement thereof will be limited by another of said stops, a soft rubber wheel journaled upon the outer end of said arm and engageable with a closing screen door to absorb the thrust thereof and permit the said door to quietly close, pivoting said arm upwardly within the door

jamb, said arm having a central elongated slot adjacent its inner end to receive said pin to permit an initial longitudinal inward non-pivotal movement of said arm upon initial engagement with said screen door, a coiled spring supported upon said arm and interposed between said pin and said arm normally resisting said initial longitudinal inward movement of said arm and adapted to return the arm to its initial position as the door comes to a dead stop, an extension of reduced width projecting axially from the rear end of said arm, and a stopper projecting normally in spaced relation to said extension but in its path of pivotal movement when said arm is moved longitudinally inward whereby upon initial longitudinal inward movement of said arm said stopper engages said extension preventing upward pivotal movement of said arm and said spring will return said arm to its initial position for pivotal movement upwardly upon subsequent closing movement of said door.

3. A screen door stopper comprising an upright plate secured within a door jamb, a headed pin projecting normally of said plate and secured thereto, an arm pivotally mounted at its inner end upon said pin and adapted to extend parallel to said plate and outwardly of said jamb, spaced stops projecting normally from said plate upon opposite sides of said arm and in its path of pivotal movement and alternately engageable by said arm to limit pivotal movement thereof, one of said stops underlying and normally supporting said arm whereby upward pivotal movement thereof will be limited by another of said stops, a soft rubber wheel journaled upon the outer end of said arm and engageable with a closing screen door to absorb the thrust thereof and permit the said door to quietly close, pivoting said arm upwardly within the door jamb, said arm having a central elongated slot adjacent its inner end to receive said pin to permit an initial longitudinal inward non-pivotal movement of said arm upon initial engagement with said screen door, a bolt mounted upon and arranged parallel to said arm with its head bearing against said pin and with its opposite end slidably engaged by said arm, a coiled spring mounted upon said bolt with one end bearing against the head of said bolt and with the opposite end bearing against said arm normally resisting said initial longitudinal inward movement of said arm and adapted to return the arm to its initial position as the screen door comes to a dead stop, and a stopper projecting normally from said plate rearwardly of said pin and arranged normally in spaced relation to the inner end of said arm but in its path of pivotal movement when said arm is moved longitudinally inward whereby upon said initial longitudinal inward movement of said arm said stopper engages its inner end preventing pivotal movement thereof and said spring will return said arm to its initial position for pivotal movement upwardly upon subsequent closing movement of said door.
